UNITED STATES PATENT OFFICE.

HORATIO N. TAFT, OF SAG HARBOR, NEW YORK.

IMPROVEMENT IN FILTERS.

Specification forming part of Letters Patent No. 122,291, dated December 26, 1871.

Specification describing a certain Improvement in Filters, invented by HORATIO N. TAFT, of Sag Harbor, in the county of Suffolk and State of New York.

The object of this invention is to furnish a new and improved filter for water and other fluids—a filter which may readily be reversed for cleaning or used without reversing; and it consists in the construction, arrangement, and combination of parts hereinafter set forth and described.

In the accompanying drawing, Figure 1 represents a vertical central section of my improved filter. Fig. 2 is a horizontal section taken on the line *x x* of Fig. 1.

Similar letters of reference indicate corresponding parts.

A is an outer cylinder or shell, of any desired shape, dimensions, or material, provided with a head, *B*, at each end, the heads being so attached to the shell that they make water-tight joints therewith. In each head is a tube, *C*, having therein a stop-cock, *D*. *E* is an inner cylinder or vessel, of one-third (more or less) the diameter of the shell *A*, and of corresponding or other shape, which has two or more perforated partitions, *F F*, therein. *G G* are two perforated dia-phragms or false heads. Upon one of the sides of each is a flange, *H*, by which the interior cylinder *E* is kept in a central position in the shell. The interior cylinder or part *E* is supported longitudinally by the perforated false heads *G G*. On the opposite or outer side of each of these false heads there is a rim-flange, *I*, which is designed to reach the outer heads *B B*, as seen in the drawing, so that the interior part *E*, while resting on the lower false head, will really be supported by the lower head *B*, instead of the flange *I*. Any other device may be employed to support the false heads; but the arrangements should be such that the false heads or either of them can be readily taken out or put in. *J J* are valves of sufficient diameter to cover the ends of the interior cylinder or part *E*. These valves may be hinged to the false heads, as seen in the drawing, or made to close down so as to cover the end and exclude water from the upper end of *E* when the filter is in operation. The lower valve will drop by its own gravity and allow the water or other liquid to pass upward, as indicated. *K K* are chambers in the ends of the filter, in which these valves work. These cham-

bers may be formed by making the heads *B* conical, in which case the shell *A* would be short enough to allow the rim or under side of the rim to rest on the false head and thus support it. The tubes *C C* are so constructed that a water-pipe may be attached by a union or screw-joint, or otherwise. In dwellings where it is designed to filter water from wells, cisterns, or streams, a tank, *L*, may be connected with the filter, as seen in the drawing, or in any other manner. From the description already given of the interior of the filter it will be seen that the cylinder *E* is divided into three compartments or chambers, the center of which, *M*, is the pure-water chamber. The other two, *N* and *O*, contain filtering material, as sponge, sand, charcoal, or other substance. The annular chamber *P* is also filled with gravel, sand, charcoal, or other filtering material. *R R* are discharge-pipes connecting with the pure-water chamber *M*, to which the discharge-cocks *S S* are attached, arranged so that when the filter is reversed for cleaning the point of discharge will not be altered.

When water is flowing into the filter the contained filtering material may be partially cleansed by opening the lower cock *D* and allowing the liquid to flow directly through. Ordinary filters can be cleansed in no other way except by removing the filtering material. By reversing or turning the filter end for end the impurities which have accumulated upon the top of the filtering material are at once discharged, when the lower cock *D* is opened and the cleansing is complete.

To facilitate the reversing of the filter I provide the outer cylinder or shell *A* with central trunnions *T T*, so that the filter may be supported thereby on a suitably-constructed frame or stand, and easily reversed thereon upon disconnecting the water-pipe or removing the tank *L*.

The perforated false heads *G G*, as well as the perforated partitions *F F*, are made of cast metal or other material of suitable strength, and may be covered on one or both sides with tin, wire-gauze, flannel, or other suitable straining material.

By removing the discharge-cocks *S S* and one of the heads *B* the entire contents of the shell *A* may be taken out.

I do not limit or confine myself to the precise form or arrangement of any of the parts herein described, as they may be varied in many ways without departing from my invention. Neither

do I confine myself to a reversible filter, as my improved filter may be used as ordinary filters are, if desired. Instead of making the shell A with flanges and connecting the heads B B thereto by bolts, as seen in the drawing, the heads of the filter may be held to the shell by a single central bolt or screw-rod, or by two or more screw-bolts or rods. In the former case the tubes C C would be placed one side of the center and the valve J would slide up and down on the bolt instead of being hinged to the false head. The valves J J may be opened and closed from the outside by means of screws or other device instead of opening and closing by their weight; but I prefer the arrangement described.

Having thus described my invention, I claim as new and desire to secure by Letters Patent—

1. A reversible filter having valves J, by means of which the flow of the water or other liquid is automatically controlled, substantially as described.

2. The chambers K K, or their equivalent, in

combination with tubes C C and valves J J, substantially as and for the purposes described.

3. The interior cylinder or part E, with perforated partitions F F therein, surrounded by the annular filtering-space P, as shown and described.

4. The perforated diaphragm or false heads G G, in combination with the inner cylinder E, substantially as described.

5. The trunnions T T, in combination with a reversible filter, when the filter is constructed substantially as described.

6. The arrangement of the discharge-cocks S S, in combination with a reversible filter, when the filter is constructed substantially as described.

7. The combination of valves J J with the interior cylinder or vessel E, as and for the purposes described.

HORATIO N. TAFT.
